[57] CLAIM

The ornamental design for an air freshener dispenser casing, as shown and described.

DESCRIPTION

FIG. 1 is a front, top and right side perspective view of an air freshener dispenser casing showing our new design;

FIG. 2 is a front elevational view thereof;

FIG. 3 is a left-side elevational view thereof;

FIG. 4 is a top plan view thereof; and

FIG. 5 is a bottom plan view thereof.

The rear of the dispenser casing shown in FIG. 1 is substantially plain. The broken line showing of other components of the air freshener dispenser casing in FIGS. 3 and 5, is for illustrative purposes only, and forms no part of the claimed design.
